(57) **CLAIM**

The ornamental design for a laundry valet rod, as shown and described.

DESCRIPTION

FIG. 1 is a front perspective view of the design of the laundry valet rod of the present invention;

FIG. 2 is a front elevation view of the laundry valet rod embodiment shown in FIG. 1;

FIG. 3 is a side elevation view of the laundry valet rod embodiment shown in FIG. 1;

FIG. 4 is a rear elevation view of the laundry valet rod embodiment shown in FIG. 1;

FIG. 5 is a bottom plan view of the laundry valet rod embodiment shown in FIG. 1;

FIG. 6 is a top plan view of the laundry valet rod embodiment shown in FIG. 1; and,

FIG. 7 is a perspective view of the laundry valet rod embodiment shown in FIG. 1 attached to an appliance (not claimed).
